(57) **CLAIM**

The ornamental design for a cover for a casement window handle, as shown and described.

DESCRIPTION

FIG. 1 is an isometric view of a cover for a casement window handle in accordance with our invention;

FIG. 2 is a front elevational view of the cover for a casement window handle of FIG. 1;

FIG. 3 is a rear elevational view of the cover for a casement window handle of FIG. 1;

FIG. 4 is a top plan view of the cover for a casement window handle of FIG. 1;

FIG. 5 is a top plan view of the cover for a casement window handle of FIG. 1;

FIG. 6 is a left side elevational view of the cover for a casement window handle of FIG. 1;

FIG. 7 is a right side elevational view of the cover for a casement window handle of FIG. 1; and,

FIG. 8 is an opposite isometric view of a cover for a casement window handle of FIG. 1.

The portions of the article in broken lines are shown for illustrative purposes only and form no part of the claimed design.
